(57) **CLAIM**

The ornamental design for a handle for a bottle, shown and described.

DESCRIPTION

FIG. 1 is a rear and right-side perspective view from above of our new design for a handle for a bottle;

FIG. 2 is a front and right-side perspective view from above of our new design of a handle for a bottle;

FIG. 3 is a rear elevational view of our new design of a handle for a bottle;

FIG. 4 is a front elevational view of our new design of a handle for a bottle;

FIG. 5 is a right-side elevational view of our new design of a handle for a bottle;

FIG. 6 is a left-side elevational view of our new design of a handle for a bottle;

FIG. 7 is a top view of our new design of a handle for a bottle;

FIG. 8 is a bottom view of our new design of a handle for a bottle; and,

FIG. 9 is a right-side elevational view of our new design of a handle for a bottle, when mounted on a bottle. The broken lines are for environmental purposes only and form no part of the claimed design.
